BREATH DEFLECTOR

Clifford E. Danielson, Minneapolis, Minn.

Application March 20, 1940, Serial No. 324,933

3 Claims. (Cl. 128—139)

My invention relates to improvements in breath deflectors for doctors, dentists, barbers, nurses, beauticians and the like, an object of the invention being to provide a simple, durable, inexpensive and readily sterilized device of this kind adapted to prevent both the attendant and the attended from being subjected to the breath from the nose and mouth of the other, and adapted also to be quickly and easily applied to and removed from the person of the user and comfortably worn without substantially interfering with the vision or action of such person.

More specifically, it is an object of my invention to provide a device of the present character comprising a guard or shield, and a mounting therefor adapted to be held in the mouth of the user and to support said guard in front of the face, shielding the user's nose and mouth.

A feature of the invention resides in providing a guard or shield that is thin, light in weight and transparent, a further feature of the invention being to provide a mounting for the guard, having a yoke adapted to be received within the mouth and to embrace the arch of the teeth, and also having a stem issuing from the crotch of the yoke and connected to the guard for supporting the same, said stem being adapted to be received between the lips.

Another feature of the invention resides in making the yoke and stem of the mounting of bendable material so that they may be readily re-formed to provide for suitably adjusting the yoke to the interior of the mouth and to provide for adjusting the stem to the lips, and the stem-supported guard to the face of the user.

An object of the invention is to supply a mounting yoke of the instant nature having a relatively large outer surface area for contact with the interior surfaces of the cheeks and lips and a relatively large inner surface area for contact with the outer surfaces of the teeth, whereby the yoke is stabilized within the mouth, a feature of the invention residing in the provision of a yoke-like fin incorporated in the yoke structure for attaining such stabilizing effect and rendering the yoke comfortable to wear.

A further feature of the invention resides in providing the mounting yoke with inwardly projecting flanges forming bits which lie between the upper and lower teeth and upon which the teeth may bite.

Other objects of the invention reside in the novel combination and arrangement of parts and in the details of construction hereinafter illustrated and/or described.

In the drawing, Fig. 1 is a view illustrating a deflector in embodiment of the present invention as it appears in use, the parts thereof not concealed within the mouth of the user, being shown in side elevation; Fig. 2 is a plan view of said deflector; Fig. 3 is a sectional view thereof taken as on the line 3—3 of Fig. 2, and Fig. 4 is a sectional view of said deflector taken as on the line 4—4 of said Fig. 2.

Reference being had to the accompanying drawing, it will be observed that the embodiment of my invention illustrated therein comprises a guard or shield 10 and a mounting therefor designated in its entirety by the reference letter A.

Said guard or shield 10 is of relatively stiff sheet-like material and is preferably transparent. It may be of any suitable size and shape and may be cut or stamped from sheet-stock or cast or molded in a form and may be dished rather than being planiform, to conform more nearly with the configuration of the face in the interests of sightlessness, and to render the action of the shield more effective in deflecting the breath from the nose and mouth of the user wearing the deflector.

The mounting A comprises a yoke-like element B and a supporting member 11 issuing from said element and connected to said guard 10.

The element B includes a yoke of bendable wire 12 and the supporting member 11 consists of a stem of bendable wire, said stem being soldered, welded or otherwise suitably joined at one end thereof to said wire yoke at the crotch thereof and being soldered or otherwise suitably attached at its other end to the guard 10.

A relatively thin fin 13 of rubber or other suitable material is incorporated in the mounting element B. This fin is attached to wire yoke 12 and preferably by molding the same thereover, employing said wire yoke as a rib. Formed integrally with each branch of the yoke-like fin 13 and at the inner face thereof is a flange 15 providing a bit.

The mounting element B is adapted to be received within the mouth of the user, the fin 13 taking position embracing the arch of the teeth, with the flanges 15 located between the upper teeth and the lower teeth and with the outer surface of said fin 13 facing the inner surfaces of the cheeks and lips and the inner surface of said fin facing the outer surfaces of the teeth. Said mounting element B being thus disposed within the mouth of the user, the bits 15 are always positioned to be clamped between the upper and lower teeth, at the user's choice, should such course be desired under circumstances such, for

example, as that attended with quick movements of the user's head.

The supporting member or stem 11 of the mounting A at the inner portion thereof adjacent to the wire yoke 12 lies between the lips of the user, the portion of said stem in continuation of said inner portion being bent first downwardly and then outwardly to suspend the guard 10 from the element B and to provide reverse pre-bent portions 11^a, 11^b where further bending may be readily effected for adjustably locating the guard 10 to best perform its intended function in use by the particular wearer thereof.

From the standpoint of construction, my improved deflector is simple, durable and inexpensive. Said deflector is easily and quickly applied to the user, it being only necessary to slip the element B of the mounting into the mouth. The guard 10 effectively shields the attended from the breath from the nose and mouth of the attendant and also shields the mouth and nose of the attendant from the breath of the attended. Under normal conditions the deflector is comfortably worn by the user without other than normal muscular tension, but on occasion may be firmly clamped in place by the bite of the user upon the flange-like bits 15. The guard 10, being transparent, does not interfere with the user's vision. The limited structure of the deflector that may be seen when the device is in use, coupled with the transparency of said guard 10, lends sightliness to the deflector. The element B comprising the mouth-piece, as well as the remainder of the structure, is readily cleansed and sterilized.

Changes in the specific form of my invention, as herein disclosed, may be made within the scope of what is claimed without departing from the spirit of my invention.

Having described my invention, what I claim as new and desire to protect by Letters Patent is:

1. In a device of the character described, a guard of relatively stiff material adapted to be worn before the face of a wearer to shield an attended person from the wearer's breath from mouth and nose and to shield the mouth and nose of the wearer from the breath of the attended person, a mounting for said guard including a

yoke-like element for reception in its entirety within the wearer's mouth, said element being bendable into retained conformity throughout its length with the outside of the arch of the wearer's teeth and adapted to be held in place relative to the teeth by the overlying portions of the face, a stem issuing from the crotch of said yoke-like element and receivable between the wearer's lips centrally of the mouth, said stem being connected to the guard and being reversely curved vertically and bendable for selective positioning of the stem relative to the meeting plane of the lips and for selective positioning of the guard relative to the mouth and nose of the wearer.

2. In a device of the character described, a guard adapted to be worn before the face of a wearer to shield an attended person from the wearer's breath from mouth and nose and to shield the mouth and nose of the wearer from the breath of the attended person, a mounting for said guard including a yoke-like element for reception in its entirety within the wearer's mouth, said element conforming throughout its length with the outside of the arch of the wearer's teeth and adapted to be held in place relative to the teeth by the overlying portions of the face, a stem issuing from the crotch of said yoke-like element and receivable between the wearer's lips centrally of the mouth, said stem being connected to the guard and being bendable for selective positioning of the stem relative to the meeting plane of the lips and for selective positioning of the guard relative to the mouth and nose of the wearer.

3. In a device of the character described, a guard adapted to be worn before the face of a wearer to shield an attended person from the wearer's breath from mouth and nose and to shield the mouth and nose of the wearer from the breath of the attended person, a mounting for said guard including an element adapted to be received and held in place within the wearer's mouth, and a member issuing from said element and receivable between the wearer's lips, said member being connected to the guard and adjustable for the selective positioning of said guard relative to the mouth and nose of the wearer.

CLIFFORD E. DANIELSON.
